(57) **CLAIM**

The ornamental design for a vehicle simulation workstation, as shown and described.

DESCRIPTION

FIG. 1 is a front perspective view of my new design for a vehicle simulation workstation;

FIG. 2 is a left side elevation view of my new invention, wherein the right side elevation view is a mirror image thereof;

FIG. 3 is a front elevation view of my new invention;

FIG. 4 is a rear elevation view of my new invention;

FIG. 5 is a top plan view of my new invention; and,

FIG. 6 is a rear perspective view of my new invention. The broken lines shown are included for the purpose of illustrating environment and form no part of the claimed design.
